UNITED STATES PATENT OFFICE.

GEORGE J. FREDERICK AND EDWARD D. HAYES, OF FAYETTEVILLE, ARKANSAS,
ASSIGNORS OF ONE-THIRD TO OSCAR L. ROGERS, OF FAYETTEVILLE, ARKANSAS.

BRIDGE-SIGNAL FOR RAILROADS.

1,178,711.

Specification of Letters Patent.

Patented Apr. 11, 1916.

Application filed March 27, 1915. Serial No. 17,576.

To all whom it may concern:

Be it known that we, GEORGE J. FREDERICK and EDWARD D. HAYES, citizens of the United States of America, residing at 5 Fayetteville, in the county of Washington and State of Arkansas, have invented new and useful Improvements in Bridge-Signals for Railroads, of which the following is a specification.

10 This invention relates to improvements in bridge signals for railroads and has particular application to an automatic signal whereby the engineers of trains approaching the bridge will be warned in the event 15 of a defect in the bridge incident to a wash-out or other cause.

In carrying out the present invention, it is our purpose to provide a railway bridge signal which will be automatically operated 20 to indicate danger in the event of the bridge being washed away or any of the supports thereof being displaced, so that the engineers of trains approaching the bridge will be notified of the condition thereof.

25 It is also our purpose to improve and simplify the general construction of railway bridge signals and to provide a signal which may be installed and maintained at a minimum expense and which will operate efficiently and effectively for its intended purpose.

With the above and other objects in view, the invention consists in the construction, combination and arrangement of parts hereinafter set forth in and falling within the 35 scope of the claim.

In the accompanying drawings; Figure 1 is a view in side elevation of a bridge equipped with a signal constructed in accordance with the present invention. Fig. 2 40 is a longitudinal central sectional view therethrough. Fig. 3 is a cross sectional view taken at right angles to Fig. 2. Fig. 4 is a horizontal sectional view through the signal mechanism. Fig. 5 is a fragmentary vertical sectional view through the bridge structure showing the connections between the weights and the main cable.

Referring now to the drawings in detail, 50 1 designates a bridge structure embodying in its construction the usual vertical supports 2 and longitudinal stringers 3 on the upper ends of the vertical supports carrying the railroad trackway 4.

Arranged at each end of the bridge structure and suitably secured to the latter is a vertical casing 5 having the top wall thereof formed with an opening 6 and a bottom wall equipped with a bearing 7 alining vertically with the opening 6. Rotatably mounted in the opening 6 and having the lower end thereof journaled in the bearing 7 is a shaft 8 and secured to the upper end of the shaft 8 and projecting upwardly therefrom is a signal post 9. Suitably connected to the signal post 9 adjacent to the upper extremity thereof and projecting in diametrically opposite directions are signal blades 10 indicative of danger, while secured to the post at diametrically opposite points and disposed in a plane at right angles to the plane of the danger blades 10 are signal blades 11 indicating safety. On the upper end of the post is fastened a signal lamp 12 having bull's eyes colored red to 75 correspond to the danger blades and bull's eyes colored green to correspond to the safety blades. Secured to the opposite side walls of the casing 5 and extending across the latter is a cross piece 13 formed with an opening through which the shaft 8 is passed and with a slot 30. Pivoted between its ends within the slot 30 is a vertical lever 31 and connected with the upper end of the lever 31 is one end of a retractile spring 32, the remaining end of the spring being fastened to the adjacent side wall of the casing. The lower end of the lever 31 engages a guide 33 secured to the bottom wall of the casing and is capable of movement within such guide. 80 Fastened to the shaft 8 below the cross piece 13 and projecting outwardly therefrom is a lug 34 having the outer end forked or bifurcated as at 35 to receive the adjacent portion of the lever 31. Encircling the shaft 8 is a 85 spring 36 having one end fastened to the shaft and the remaining end secured to an adjacent wall of the casing and this spring acts to rotate the shaft 8 and signal post 9 to dispose the danger blades 10 at right angles to the trackway and the safety indicating blades 11 parallel with the trackway. Normally, the retractile spring 32 holds the lever 31 in engagement with the forked end of the lug 35 and so prevents rotation of the 90 shaft 8 under the action of the spring 36, thereby maintaining the safety blades in a position at right angles to the trackway so

as to be visible to an engineer of an approaching train and the danger blades parallel with the trackway.

Extending longitudinally of the bridge structure and preferably disposed below the trackway 4 is a tube 15 formed of axially alining sections 16. The meeting ends of the sections 16 are preferably disposed immediately above the vertical supports 2 and 10 interposed between the meeting ends of the sections 16 are boxes 17 having the opposite walls thereof formed with openings through which the ends of the particular sections 16 pass. Rotatably mounted upon horizontal axles carried by the side walls of each box 17 and disposed within the latter are guide sheaves 18 appropriately spaced apart and disposed in parallelism and having the grooved peripheries thereof alining with 20 the ends of the sections 16 respectively of the tube. Connected with the side walls of the respective casings 5 and projecting outwardly therefrom toward the center of the trackway are tubes 37 and the outer ends 25 of the tubes 37 extend into boxes 38 and also extending into the boxes 38 are the adjacent ends of the tubes 15 respectively and the tubes 37 are disposed at right angles to the tubes 15, owing to the positions of the 30 casings 5. Connected with the lower ends of the levers 31 in the respective casings 5 are the opposite ends of a cable 22 or other flexible element that extends through the tubes 37 and the sections of the tube 15 35 and the boxes 17 above the guide sheaves 18, the portions of the cable 22 within the boxes 38 being trained over guide sheaves 39 to facilitate the movement of the cable. Secured to one face of each vertical support 2 a suitable distance below the adjacent box 17 is a vertical casing 23 and closing the upper end of the vertical casing 23 is a cover 24 formed centrally with an opening and uprising from the cover 24 is a sleeve 40 25 alining axially with the opening in the cover and having the upper end thereof passed through the bottom wall of the adjacent box 17 and disposed between the guide sheaves 18. Connected with the cable 22 45 and extending downwardly therefrom between the guide sheaves 18 of the respective pairs of such sheaves are branch cables 26 and these branch cables pass through the respective sleeves 25 into the vertical casings 23 and connected with the lower end 50 of each branch cable 26 is a weight 27 disposed within the casing 23.

In practice, should any one of the supports 2 be displaced, or the track structure

60 moved relatively to the supports, the particular weight 27 will be relieved of the influence of the casing 23 and exert a downward pull upon the branch cable 26 and the main cable 22. When a pull is exerted upon the main cable 22, the levers 31 are swung 65 about their pivotal connections with the respective cross pieces 13 and disengage the forked ends of the lugs 34, thereby releasing the shafts 8 so that the latter may be rotated under the action of the respective 70 springs 36. As the shafts are rotated under the action of the springs, the safety blades are moved to a position parallel to the trackway, while the danger blades are disposed at right angles to the trackway so that the 75 engineer of a train approaching the bridge will be advised as to the condition of the bridge. When the signal post is rotated to move the danger blades to active position and the safety blades to inactive position, 80 the lamp on the upper end of such post is similarly actuated and the bull's eyes indicative of danger are visible to the engineer, while the bull's eyes indicating clear are disposed in positions corresponding to the 85 positions of the safety blade.

While we have herein shown and described the preferred form of our invention by way of illustration, we wish it to be understood that we do not limit or confine 90 ourselves to the precise details of construction herein described and delineated, as modification and variation may be made within the scope of the claim without departing from the spirit of the invention. 95

We claim:

In bridge signal apparatus, vertical signal posts located at each end of the bridge structure, a vertical shaft connected to the lower end of each signal post, danger and safety signal blades on said posts, means acting upon said shaft to rotate said signal posts to render the danger signal blades active and the safety signal blades inactive, a lever pivoted between its ends for swinging movement, a lug carried by said shaft and normally engaged by said lever to hold the shaft against movement under the action of said means, and means for swinging said lever to release said shaft. 105

In testimony whereof we affix our signatures in presence of two witnesses.

GEORGE J. FREDERICK.
EDWARD D. HAYES.
